(57) **CLAIM**

The ornamental design for a computer, as shown.

DESCRIPTION

This computer is used as server.

FIG. 1 is a top perspective view of the computer;

FIG. 2 is a bottom perspective view of the computer;

FIG. 3 is a front view of the computer;

FIG. 4 is a back view of the computer;

FIG. 5 is a right view of the computer;

FIG. 6 is a left view of the computer;

FIG. 7 is a bottom plan view of the computer; and,

FIG. 8 is a top plan view of the computer.

1 Claim, 6 Drawing Sheets

FIG. 1

FIG. 2

FIG. 3

FIG. 4

FIG. 5

FIG. 6

FIG. 7

FIG. 8
